DESIGN FOR A PORTABLE FOLDABLE GRILL

Udo K. Johannsen, Cortland, N. Y., assignor to
The Brewer-Titchener Corporation, Cortland,
N. Y., a corporation of New York

Application April 30, 1945, Serial No. 119,315

Term of patent 14 years

(Cl. D81—10)

To all whom it may concern:

Be it known that I, Udo K. Johannsen, a subject of the Kingdom of Denmark, residing at Cortland, in the county of Cortland and State of New York, United States of America, have invented a new, original, and ornamental Design for a Portable Foldable Grill of which the following is a specification, reference being had to the accompanying drawing, forming part thereof.

folding grill showing my design in its upright position.

Figure 2 is a view showing my portable foldable grill in an inverted folded position with the ash pan omitted for convenience of illustration.

I claim:

The ornamental design for a portable foldable grill, as shown.

UDO K. JOHANNSEN.
